UNITED STATES PATENT OFFICE.

JEAN EMILE CHOLTUS AND HUBERT JEANNERSON, OF PARIS, FRANCE.

STOVE.

939,890.

Specification of Letters Patent.

Patented Nov. 9, 1909.

Application filed July 7, 1908. Serial No. 442,335.

To all whom it may concern:

Be it known that we, JEAN EMILE CHOLTUS and HUBERT JEANNERSON, citizens of the Republic of France, and residents of 5 Paris, France, have invented a new and useful Stove, which is fully set forth in the following specification.

This invention relates particularly to kitchen-ranges or cooking stoves of the class 10 in which provision is made for utilizing the range and stove both for cooking and for heating the premises in which the stove is used.

The object of this invention is to produce 15 a stove of the kind above referred to having provision for the efficient heating of a large volume of air and for the equable distribution of the heated air in the heating compartments of the stove and among the 20 flues or pipes through which it is distributed to the various rooms or points at which it has to be used.

To the above end the invention consists in the improved stove or range hereinafter described and as defined in the succeeding 25 claim.

An embodiment of the present invention is illustrated in the accompanying drawings.

Figure 1 is a vertical section looking from 30 front to back of the stove on the line A—A, in Fig. 2, Fig. 2 is a sectional plan-view on the line B—B, in Fig. 1, Figs. 3 and 4 are detail plan-views of the perforated plates for controlling the movement of drawing off 35 and distribution of air, and Fig. 5 is a perspective front view of the stove with the top removed to disclose the interior.

The illustrated embodiment of the invention is a cooking stove or kitchen-range having 40 the general form characteristic of such devices. It has a fire-pot 9 and an ash-pit e of ordinary form. At the right hand of the fire-pot is the oven d which is provided with a door 11 at the front of the stove. The 45 products of combustion from the fire-pot are carried over the top of the oven through a passage m formed between the oven and the top of the stove as indicated by the arrow 1. The hot gases then pass downward at the 50 right hand side of the oven through a passage 2 and then into a passage 3 beneath the oven. From the passage 3 the products of combustion escape through a flue n which may be connected with a chimney in the 55 usual manner.

To provide for heating air, the fire-pot

and ash-pit and the oven are inclosed on three sides and the bottom by air-chambers. The lowermost air-chamber 8 which may be designated as the cold air-chamber, receives 60 air through an air inlet-pipe a which may draw air from any convenient point and preferably from the building in which the stove is used. From the air-inlet pipe a, the air passes vertically through hollow up- 65 rights b b' into the cold air-chamber 8 where it is to some extent warmed by contact with the inner partition 4, forming the bottom of passage 3. From the cold air-chamber a portion of the air rises into a 70 lower heating chamber f inclosing the ash-pit e. Another portion of the air rises through the openings in a perforated plate h at the right hand end of the stove and enters a heating chamber 7 where it is heated 75 by contact with the metal wall of the passage 2. A third portion of the air from the cold air chamber 8 passes through the openings o of the perforated plate c and enters a rear heating chamber 6 at the back of the 80 stove.

The air in the heating chamber f, after being warmed by contact with the ash-pit e rises through a perforated plate g which surrounds the fire-pot on three sides as 85 shown in Figs. 2 and 5 and enters an upper heating-chamber 10, inclosing the fire-pot, where it is heated to a high degree. The heated air in the rear heating chamber 6 is drawn off through distributing pipes or flues 90 j, k through which it may be delivered to any point desired. The heated air in the upper heating chamber 10 is drawn off through similar pipes j'. In order to equalize the pressure in the heating chambers 6 95 and 10 and the flow of air through the several distributing pipes, the heating chambers 6 and 10 are connected by an opening x. The several perforated plates, including plates g and h, in particular help to equalize 100 the flow of air through the several heating chambers and to break up local currents therein, so that the air is heated uniformly and delivered at a uniform and convenient temperature through the several outlet pipes. 105

When the oven is not in use, it may be utilized to add to the supply of hot air by opening a slide l which normally closes, an opening l' at the back of the oven and thereby affording an outlet from the oven to the 110 heating chamber 6. When, on the other hand, it is desired to use the stove only for

cooking purposes, as for example, in hot weather, the air heated by the stove may be delivered out-doors by arranging one of the distributing pipes to extend to the outside 5 of the building. In such a case the heating chambers, inclosing the fire-pot and the oven, act effectively to keep the outside of the stove cool and thereby prevent overheating of the room in which the stove is used.

10 In order to economize the heat of the stove, heat-insulating material is employed at the points of highest temperature. A body of such material is used at i' opposite the fire-pot where the radiations from the fire-pot to 15 the outer wall of the stove is greatest and another body of insulating material is used at i at the right hand side of the stove where the hot gases from the fire-pot strike against the end-wall in turning downward into the 20 passage 2.

Various modifications may be made in the embodiment of our invention hereinbefore described and illustrated in the accompanying drawings within the nature of the invention and the scope of the claim. 25

We claim—

A stove having walls and partitions form-

ing an oven, a fire-box, an ash-pit, a flue for heating the oven passing from the fire-box over and under the oven, a cold-air chamber 30 beneath the lower part of the flue, an upper chamber surrounding the fire-box, a lower heating chamber adjacent to the ash-pit and communicating with the cold-air chamber, a rear heating chamber at the rear of the 35 oven, distributing pipes communicating with the upper heating chamber, distributing pipes communicating with the rear heating chamber, and means for conducting air to the cold-air chamber, the rear 40 wall of the oven being provided with a closable opening connecting the oven and the rear heating chamber, and perforated partitions being provided between the upper and lower chambers and the cold-air and rear 45 heating chambers respectively.

In testimony whereof we have signed this specification in the presence of two subscribing witnesses.
